[57] CLAIM

The ornamental design for a portable corral panel, substantially as shown.

DESCRIPTION

FIG. 1 is a front elevational view of a portable corral panel showing my new design;

FIG. 2 is a rear elevational view thereof;

FIG. 3 is a front perspective view thereof;

FIG. 4 is an enlarged fragmentary sectional perspective view taken along line 4—4 in FIG. 3;

FIG. 5 is an end elevational view thereof, the opposite end being identical;

FIG. 6 is a top plan view thereof; and

FIG. 7 is a bottom plan view thereof.

FIG. 1

FIG. 2

FIG. 3

FIG. 4

FIG. 5

FIG. 6
